UNITED STATES PATENT OFFICE.

JAMES C. ALEXANDER, OF ABERDEEN, WASHINGTON.

SHINGLE-PACKAGE.

No. 851,789.

Specification of Letters Patent.

Patented April 30, 1907.

Application filed March 29, 1906. Serial No. 308,766.

To all whom it may concern:

Be it known that I, JAMES C. ALEXANDER, a citizen of the United States, residing at Aberdeen, in the county of Chehalis and 5 State of Washington, have invented certain new and useful Improvements in Shingle-Packages, of which the following is a specification.

This invention relates to an improved 10 method of packing shingles in bundles and has for its object the provision of improved means for spacing the shingles apart, whereby when the bundles of shingles are placed in a kiln to be dried, the heat may act upon 15 both sides of the shingles to effect a more rapid and thorough drying thereof, than is the case where the shingles are bound together in solid bundles and in relatively contacting relation.

20 A further object of the invention is the provision of means for spacing the shingles apart when it is desired to impregnate them with creosote or other preservative or to coat them with paint.

25 A further object of the invention is the provision of an improved parting strip for spacing the shingles apart. This parting strip is constructed in such a manner that it presents the least possible area of contact to the adjacent shingles between which it is disposed.

30 In connection with my improved parting strip, novel means are provided for withdrawing a plurality of them simultaneously from the bundles.

35 The detail construction will appear in the course of the following description, in which reference is had to the accompanying drawings forming a part of this specification, like numerals designating like parts throughout 40 the several views, wherein,

Figure 1 is a side elevation of a bundle of shingles, the shingles comprising said bundle being spaced apart by my improved parting strip, Fig. 2 is an end elevation of the bundle 45 illustrated in Fig. 1, and Fig. 3 is a detail perspective view of a corrugated metallic parting strip.

Referring to the drawing, the numeral 5 designates a bundle of shingles composed of a 50 plurality of shingles 6. These shingles are spaced apart by the corrugated metallic parting strips 7 having openings 8 formed in their ends. The bundle formed by the assemblage, in the manner shown in Fig. 1 of 55 the shingles and parting strips, is bound together by any desired form of clamp 9, a

conventional embodiment of which is shown, comprising upper and lower binding strips of wood 10 and metallic tie rods 11 secured at their ends, as at 12, to the strips 10 and 60 uniting the same on each side of the bundle.

The corrugated parting strips 7 are disposed transversely of the bundle and their ends project on each side beyond the side of the shingles, and in this arrangement the 65 openings 8 are in vertical alinement throughout the entire series of parting strips, for the reception of a rod 13, by which any number of parting strips desired, or the entire series if necessary, may be removed.

70 In the practical use of my invention, shingles are assembled as shown in Fig. 1, being arranged in pairs having their enlarged ends projecting. These pairs are spaced away from one another by the corrugated metallic 75 parting strips 7 which are disposed transversely therebetween, and have contact with the shingles only at the apices of their corrugations. The outer ends of the several shingles which are to be coated or impregnated 80 are thus arranged in spaced relation throughout the entire series. When the bundle has been bound together by the clamp 9 the rods 13 are inserted through the ends of the parting strips and the bundles are then placed in 85 the kiln and thoroughly dried.

Upon the completion of the drying operation, the bundles of shingles are removed from the kiln. Prior to packing for shipment, the bundles may be given a bath in 90 the paint or preserving fluid with which they are to be impregnated. When it is desired to pack the bundles for shipment, the entire series of parting strips can be withdrawn from either side of the bundle by using one of 95 the rods 13 as a handle. When the parting strips have thus been withdrawn from the bundles the shingles are placed in a packing frame and are repressed and retied with the clamp 9 at which time they are ready for 100 shipment.

105 It has been found that owing to the more perfect circulation of heat, only a small portion of the time required for drying shingles when the shingles are packed closely together is required when the shingles are spaced apart. The degree to which the shingles are dried is equal throughout the bundle when the art is practiced in accordance with the present invention, since it is 110 not necessary to apply as much heat to the shingles, when the heat can act on both sides

thereof as is the case when the heat must penetrate from the outside of a bunch of closely packed shingles. This is a marked advantage over the art as heretofore practiced for excessive heating injures the shingles and reduces their value commercially.

Having fully described my invention, I claim:

A shingle package comprising a plurality of shingles arranged in spaced superposed pairs and parting strips inserted between the adjacent pairs and affording uninterrupted

passages between said pairs throughout the area of the shingles, each of said parting strips comprising a member formed in its direction of greatest length with comparatively deep corrugations having comparatively sharp apices. ¹⁵

In testimony whereof I affix my signature in presence of two witnesses.

JAMES C. ALEXANDER.
